UNITED STATES PATENT OFFICE.

MAURICE ALLAND, OF ATLANTIC CITY, NEW JERSEY.

RECEPTACLE CLOSURE.

Application filed January 30, 1926. Serial No. 84,876.

The object of the invention is to provide improvements relating to closures for such containers as those in which milk and similar liquids are distributed, and more particularly to means whereby said closure is adapted to be removed from a container.

Having particularly, though not exclusively, in mind the well known bottle in which milk is shipped and quite universally handled in retail quantities, and the so-called cap, or disc closure, that is used with little or no exception, the present invention has for an object the provision of a relatively small button, readily formed of inexpensive material, which is normally inserted in one direction through a previously provided, preferably eccentric aperture in such a cap, and thereafter is positively prevented from being withdrawn from said aperture, due to the closing of the sides of the aperture about a restricted portion of the button, without mutilating or at least weakening said cap or closure.

Another object, therefore, is to provide an integral button for this purpose, comprising a head upon one end, much larger than the diameter of the aperture provided for the button in a bottle cap, the other end of said button being slightly smaller than the diameter of said aperture, and comprising a peripheral flange beneath which one's finger-nails can easily enter for gripping the same, the central portion of said button comprising two intermediate sections, that one nearer to the larger head having a diameter equal to that of the aperture in the cap, and terminating in the direction towards the nail-engaging head in an abrupt radial flange, larger than said first section and adapted to be quickly forced through said aperture, by momentarily stretching but not tearing the aperture's side walls, and the second of said intermediate sections thence tapering from said flange towards said nail-engaging head.

With these objects in view, the details of the construction and operation of the invention in its preferred embodiment are fully brought out in the following description, when read in conjunction with the accompanying drawings, in which Fig. 1 is the upper portion of a milk bottle (or similar container, which is represented herein-after by the term "bottle") shown partly in section, and provided with a disc closure or cap equipped with a button of the char-

acter above referred to; Fig. 2 is a top plan view of the same; Fig. 3 is an enlarged vertical diametrical section of the closure and button operatively united; Fig. 4 is a side elevation of the button *per se*; and Fig. 5 is a top plan view of the same.

Referring to the drawings, the upper portion 1 of a bottle is shown as comprising a cylindrical flange 2, terminating downwardly in a peripheral plane shoulder 3, surrounding the usual axial bore 4, through which the liquid contents are adapted to be inserted and removed from the bottle. It is the usual practise to bridge the top of such a bottle with a disc closure 5, commonly known as a cap, and there have been provided several different constructions and arrangements for removing said cap without damaging the bottle, which is usually made of glass, or spilling the contents therefrom, which usually extend into close proximity with the under surface of said cap, all with greater or lesser success.

The present invention comprises, first the provision of an aperture 6, extending through the said disc closure and eccentrically positioned with respect to the center of the same. The button or knob, shown in detail in Figs. 4 and 5, comprises upon its normally lower portion an enlarged head 7 adjacent to which head the said button comprises a relatively more slender cylindrical shank portion 8, terminating upwardly in an abrupt radially projecting flange 9. Continuing still upwardly, said button tapers at 10 in any desired configuration, until its surface abruptly meets a radially projecting circumferentially extending flange 11, which forms a manually engageable head 95 of less diameter than that of the flange 9, and of the same or preferably less diameter than the cylindrical shank portion 8.

In the operation of this invention the disc closure or cap is provided with the aperture 6 above mentioned, and one of said buttons is either manually or automatically (by properly designed machinery) forced through said aperture with the head 11 preceding, said head passing through the aperture partly or entirely out of touch with its walls. When the flange 9 reaches the aperture and passes rapidly therethrough, the aperture sides are quickly deflected and thus sprung out of their normal plane relationship, and spring back into the position shown in Figs. 1 and 3, upon the passage

of said flange. The aperture sides, which would be permanently stretched and perhaps mutilated by a slow passage of the flange 9 thereby, are in no way affected when the button is thus quickly inserted therethrough. Furthermore, the width of the shank 8 is slightly greater than the thickness of the cap closures 5, in order that the latter when reaching the head 7 will 10 have passed freely beyond the flange 9, and the material of the cap will be entirely released therefrom.

Having thus described my invention, what I claim and desire to protect by Letters Patent of the United States is:—

1. The combination of a disc closure having an aperture, with a button normally extending through said aperture, said button having a head upon one end operative to prevent passage of the button through the aperture in the opposite direction, a manually engageable head upon the other end of said button, and an intermediately positioned flanged operative to prevent removal 25 of the button from the aperture in the direction of said first-named head.

2. The combination of a disc having an aperture, with a button having a shank portion positioned in said aperture, a head upon one end of said shank portion larger than said aperture, the other end of said shank portion terminating in a peripheral flange adapted to be passed quickly through said aperture, and operative to prevent removal through said aperture in the opposite direction.

3. The combination of a disc having an aperture, with a button having a shank portion positioned in said aperture, a head upon one end of said shank portion larger than said aperture, the other end of said shank portion terminating in a peripheral flange adapted to be passed quickly through said aperture, and operative to prevent removal through said aperture in the opposite direction, and a manually engageable head of no greater diameter than said shank portion carried by the opposite end of said button.

In testimony whereof I hereto affix my signature.

MAURICE ALLAND.
